inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawing, wherein:

Figure 1 is a transverse section through a portion of a cylinder, piston and packing therefor, embodying the features of this invention;

Figure 2 is an enlarged section of a portion of the section shown in Figure 1; and

Figure 3 is an enlarged transverse section of a portion of another form of cylinder, piston and packing therefor.

The forms of the invention illustrated differ, primarily, in that the one shown in Figures 1 and 2 has auxiliary spring actuated means to assist in pressing a portion of the packing against the cylinder wall and that the packing portion, so acted upon, is relatively longer than the corresponding portion of the packing of the form shown in Figure 3. Otherwise the features of this invention are equally applicable to both forms. In the following description the term, fluid pressure, is to be understood to include pressure applied by means of compressed air, gas or liquids, including oil, water or molten metal.

A cylinder 11, having its bore 12 connected to a suitable source of fluid pressure by a port 13, has a piston 14 disposed therein for free reciprocating movement between its walls 15. The port 13 may serve as an inlet and exhaust port and is shown in communication with the cylinder bore 12 between the cylinder head 16 and the piston 14. The head end of the piston 14 is circularly recessed as at 17 and a circular plate 18 is disposed in the recess 17. The plate 18 is adapted to freely slide longitudinally in the recess 17 and rest against the recessed surface 19, a bolt 21 being provided to prevent the plate 18 from entirely moving out of the recess, it being understood that fluid pressure imposed against the end face of the plate 18 normally holds it in the recess 17 firmly against the recessed surface 19. The plate 18 has a circular raised portion 22 upon its outwardly facing surface, which is of smaller diameter than the plate 18 thereby providing an annular longitudinally directed shoulder 23 and an annular laterally disposed seat 24.

A metallic piston ring or packing 25, generally inverted U shaped in cross-section, and having a laterally disposed inwardly directed annular flange 26 is provided. The internal diameter of the flange 26 is of proper dimension to snugly fit about the shoulder 23 of the raised portion 22 of the plate 18, whereby the ring 25 is centered in respect to the plate 18 and, through it, in respect to the piston 14. Between one face of the flange 26 and the seat 24 of the plate 18, a gasket 27 may be disposed, and an annular member 28 is placed upon the other face of the flange 26. Screws 29, passed through the member 28, the flange 26, and the gasket 27, thread into the plate 18 and securely clamp these parts thereto. The internal diameter of the member 28 also snugly fits about the shoulder 23 and the member 28 is centered thereby.

Referring now to the form shown in Figures 1 and 2, the flange portion 26 of the piston ring 25 extends laterally from one arm 31, of the inverted U cross-sectional shape thereof, which arm 31 ex-

tends in snug contact with and along the circumferential surface of the plate 18, toward the piston wall 19. The curved portion 32 of the inverted U cross-sectional shape curves over and outwardly toward the cylinder wall 15, being spaced from the end of the piston wall 19 a determined amount. The other arm 33 of the inverted U cross-sectional shape, is longer than the arm 31 and extends away from the end of the piston wall 19 along, and in contact with, the cylinder wall 15. The end of the arm 33 is provided with an inclined inner surface 34 against which a correspondingly inclined outer surface 35 of a ring shaped expander 36 is constantly pressed. The expander 36 is provided with an annular body portion 37 about which, at suitable intervals, is disposed pockets 38, in each of which is a spring 39. The springs 39 are arranged to react between the inner ends of the pockets 38 and the opposing surface 41 of the members 28 to constantly cause the inclined surface 35 to press the end of the arm 33 outwardly and tightly against the adjacent cylinder wall. Herein the body portion 37 of the expander 36 is disposed between the arms 31 and 33 of the inverted U cross-sectional shaped portion of the piston ring 25.

It will be understood when referring to the arms 31 and 33, that reference is made to the sides of the U cross-sectional shaped portions of the piston ring 25 and that these arms are each the cross-section of cylindrical members, which are connected by the annular portion, which is referred to above as being the curved portion 32. The metallic material, of which the ring 25 is made, is preferably inherently resilient and is bent away from the outer periphery of the flange 26 to form the portion 31, then folded over to form the portion 32, and then bent toward the flange 26 substantially parallel with the portion 31 to form the portion 33, the outer surface of which is preferably ground to fit the internal diameter of the cylinder 11.

The material constituting the flange 26 is of a determined thickness whereby it is of sufficient strength to resist bending adjacent the portion 31 when in normal use. The thickness of the material constituting the portion 31 is of a determined dimension whereby it will be maintained against the circumferential surface of the plate 18 during normal use, due to its stiffness. From the portion 31 from which the curved portion 32 extends, the material is gradually tapered or thinned to a smaller dimension adjacent the portion 33.

The thickness of the material of the portion 32 is determined to be sufficient to permit slight bending or elongation of the curve laterally adjacent the portion 33, but is proportioned to prevent excessive elongation of the curve longitudinally with respect to the cylinder 11, whereby it might engage with the end surface 19 of the piston 14 from which it is spaced. From where the portion 32 is adjacent the portion 33, the material constituting portion 33 is gradually tapered or thinned to the free end 46 thereof whereat it is slightly enlarged to form a rib 47, upon the internal surface of which the inclined surface 34 is formed. The thickness of the material of the portion 33 is determined to be sufficient to insure expansion of the free end 46 into close sealing contact with the cylinder wall 15 by the inherent resiliency thereof, being assisted by the expander 36, which is provided to act as an auxiliary expanding means to insure tight sealing between the ring end 46 and the cylinder wall 15.

16, to prevent fluid under pressure leaking there-between, and to reinforce the free end 46 during the assembly of the piston into the cylinder 11. Herein, as shown in Figures 1 and 2, the space 48 between the portions 31 and 33 is connected with the fluid under pressure, due to the expander body 47 being spaced from the annular member 28 and the portion 31.

Referring to the form shown in Figure 3, the piston ring 49 is formed of inherently resilient metallic material in the same manner as the ring 25, of the form shown in Figures 1 and 2. The ring 49, however, does not have the free end 51 of the folded over portion 53 extended beyond its flange 54 and no rib nor inclined surface is provided. In this form the portions 52 and 53 are connected by a curved portion 55. In this instance, the natural inherent resiliency of the material is relied upon, due to the formation of the component portions of the ring 49 to maintain the free end 51 thereof in close sealing engagement with the cylinder wall 15, and, therefore, no auxiliary expanding means is provided.

An annular member 56 is provided and is disposed upon the flange 54 of the ring 49 to clamp the ring to the plate 18 by means of screws 57, as in the previously described form. The member 56, however, differs from the member 28 in that it extends fully across the cylinder 11 into close relationship with the wall 15 thereof and suitable openings 58 are provided, spaced at intervals to permit the fluid, under pressure, to flow into the space 59 between the portions 52 and 53. The member 56 by overhanging the free end 51 of the portion 53 protects it, as well as assists in centering the piston, as it is assembled into the cylinder 11.

Due to the particular formation of the piston rings 25 and 49, as above described in respect to the ring 25, it being understood that both are similarly formed with the exception that the rib 47 on the ring 25 with its inclined surface 34 and the expander 36 are omitted on the ring 49, the following efficient sealing action takes place when the device is in operation. When fluid under pressure is admitted through the port 13 into the cylinder 11, between its head 16 and the piston 14, the pressure thereof is imposed upon the end of the piston through the plate 18 and upon the ring 25 or 49, by the admission of fluid under pressure, into either the space 48 or 59 between the portions 31 and 33 or the portions 52 and 53, as the case may be. Due to the inherent resiliency of the portion 33 of the ring 25 with the assistance of the expander 36 and the inherent resiliency of the portion 53 of the ring 49, the rings 25 and 49 respectively, are sealed against fluid leakage between the same and the cylinder wall 15, and the piston 14 will be moved in the cylinder 11.

In pressure operated devices, such as hydraulic presses, the pressure upon the piston to move it during most of its stroke is less than the pressure required when the press is operating to compress the produce being acted upon and, therefore, only needs to be sufficient to overcome the weight of the piston and the friction between the movable parts of the press. Under these conditions, the inherent resiliency of the rings 25 and 49 is sufficient to maintain a tight seal between the same and the cylinder wall 15, but as the fluid pressure increases, for instance, when the piston approaches the working portion of its stroke, the increased fluid pressure imposed upon the ring within the respective spaces 48 and 59 tends to

expand the respective ring and separate the respective portions 31 and 33 or 52 and 53.

The formation of the rings 25 and 49, as above described, with the portions 31 and 52 of sufficient thickness to prevent bending or stretching movement; forming the respective portions 32 and 55 by gradually tapering them in thickness between their respective jointures with the portions 31 and 33 or 52 and 53, to insure a tapering bending tendency thereto; and forming the portions 33 and 53 by gradually tapering them in thickness from their connections to their free end; results in the free end being increasingly pressed against the cylinder wall 15 upon the application of increasing pressures, and the contacting area thereof increasing in proportion to the increase in the applied pressure. Due to this formation of the rings 25 and 49, the tendency to separate the portions 31 and 33 or 52 and 53, when the pressure increases, results in a movement of the portions 33 and 53 into closer contact with the cylinder wall 15, which contact gradually extends in area from the free end of the respective member toward the piston. In this manner the piston rings 25 and 49 are automatically contacted against the cylinder wall 15 over gradually increasing area from the free ends of each, which from the beginning, are constantly in contact with the cylinder wall, in accordance with, and proportional to, increases in pressure, and without any disproportionate increase in friction, the friction only increasing as the area of contact increases. Thus, under low initial pressure, the friction is of minimum degree and increases only as the pressure increases whereby the percentage of efficiency of the device remains substantially constant during all degrees of applied fluid pressure.

By the provision of the above described forms of metallic piston rings for a hydraulic press or like mechanism, the disadvantages of previously used forms are eliminated or overcome and an efficient and comparatively inexpensive packing is provided. The provision of the novel piston ring securing means and the combined elements as above described in the structure of a piston and piston ring combination are also conducive toward the efficiency of the device. The determined amount of taper given to the rings 25 and 49 from the respective flanges 26 and 54 to the free edges thereof will be understood to be mathematically determined to cause the results above described, and the respective rings may be termed as being either substantially inverted U shape in cross-section with the arms of the U shape tapered in thickness a determined amount or, as being of material in hollow cylindrical form, the wall of which is tapered a determined amount from one edge to the other, with one portion folded over the other and spaced therefrom. The rings may also be defined as being constituted by joined together superimposed hollow tapered wall cylindrical members, the wall of the outer member being thinner than that of the inner member and tapered a determined amount.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

1. In combination, a piston, a cylinder in which said piston is disposed, a plate disposed upon the end face of said piston, a metallic piston ring having an annular member disposed upon said plate, and an annular part, generally inverted U shape in cross-section, extending from and about the periphery of said member with one of the arm portions of the U shape extending over and about the periphery of said plate, with the curved base portion thereof extended toward and spaced from the end face of said piston, and with the other arm portion of the U shape extending along and in contact with the adjacent wall of said cylinder, 5 a flat annular plate disposed upon said annular member of said ring and extending over and free from contact with said U shaped part into close proximity with the wall of said cylinder and adapted to allow fluid under pressure to be received in the U shaped part between the aforesaid arm portions thereof, means to clamp said annular plate and said annular member to said plate, and means to secure said plate to the end face of said piston.
2. In combination, a piston having a circular recess in its end face, a cylinder in which said piston is disposed, a circular plate disposed in the aforesaid recess and extending axially outwardly from the end face of said piston, a metallic piston ring having an annular flange, said flange being disposed upon and secured to said plate, a hollow cylindrical member extending from the outer periphery of said flange toward the end face of said piston, about and in contact with the periphery of said plate, another hollow cylindrical member spaced from and overlying the first member, and in contact with the wall of said cylinder, and a curved annular member spaced from the end face of said piston and connecting said members adjacent the end face of said piston.
3. In combination, a piston having a circular recess in its end face, a cylinder in which said piston is disposed, a circular plate disposed in the aforesaid recess and extending axially outwardly from the end face of said piston, a metallic piston ring having an annular flange, said flange being disposed upon and secured to said plate, a hollow cylindrical member extending from the outer periphery of said flange toward the end face of said piston, about and in contact with the periphery of said plate, another hollow cylindrical member spaced from and overlying the first member, and in contact with the wall of said cylinder, and a curved annular member spaced from the end face of said piston and connecting said members adjacent the end face of said piston, the walls of said second hollow cylindrical member and of said curved annular member, being tapered in thickness a determined amount from the jointure of said curved member with said first cylindrical member to the free end of said second cylindrical member.
4. In combination, a piston reciprocable in a cylinder, a piston ring of resilient metal having 65 component portions including, a cylinder wall engaging first portion, hollow cylindrical in form, a piston engaging second portion disposed within said first portion and being hollow cylindrical in form and integrally connected in union with the first portion by a curved annular third portion, the walls of said first and third portions being reduced a determined amount in thickness from the point of connection of said third portion with said second portion to the free edge of said first portion, the reduction in thickness of the walls
- of said first and third portions being so proportioned as to permit expansion of the ring to cause the area of contact of said first portion with the cylinder wall to be increased in direct proportion to the fluid pressure imposed thereon, and an annular flat member integrally formed with, extending about and from, the inner periphery of said second portion to secure the piston ring to the end of said piston.
5. A packing ring of resilient metal for a piston or the like, comprising component portions consisting of a first and outer cylindrical hollow portion having a substantially straight outer periphery adapted to lie flat against a cylindrical surface, an inner cylindrical hollow portion within the first portion and having substantially straight parallel inner and outer peripheral surfaces, and a connecting portion substantially semi-circular in cross section, said connecting portion and said outer cylindrical portion being respectively reduced a determined amount in wall thickness from the thickness of the wall of said inner cylindrical portion at its point of connection with the connecting portion to the free edge of said outer cylindrical portion, the reduction in thickness of said connecting portion and said outer cylindrical portion being so proportioned that fluid pressure imposed against the ring between the inner and outer portions will spring the outer portion outwardly, and laterally elongate the connecting portion to increase the area of contact of the outer portion upon the wall of a cylinder or the like in direct proportion to the pressure so imposed.
6. A packing ring of resilient metal for a piston or the like, comprising component portions 35 consisting of a first and outer cylindrical hollow portion having a substantially straight outer periphery adapted to lie flat against a cylindrical surface, an inner cylindrical hollow portion within the first portion and having substantially straight parallel inner and outer peripheral surfaces, and a connecting portion substantially semi-circular in cross section, said connecting portion and said outer cylindrical portion being respectively reduced a determined amount in wall 40 thickness from the thickness of the wall of said inner cylindrical portion at its point of connection with the connecting portion to the free edge of said outer cylindrical portion, the reduction in thickness of said connecting portion and said outer cylindrical portion being so proportioned that fluid pressure imposed against the ring between the inner and outer portions will spring the outer portion outwardly, and laterally elongate the connecting portion to increase the area 45 of contact of the outer portion upon the wall of a cylinder or the like in direct proportion to the pressure so imposed, and an annular flat ring shaped portion extending about and from the inner periphery of said inner cylindrical portion 50 substantially at right angles thereto, whereby the packing ring may be secured to the end surface of a piston or the like.
7. In combination, a piston reciprocable in a cylinder, a piston ring of resilient metal having 65 component portions including, a cylinder wall engaging first portion hollow cylindrical in form, a hollow cylindrical second portion disposed within the first portion connected to the piston and being connected to the first portion by a curved 70 annular third portion, the walls of said first and third portions being gradually reduced in thickness from the point of connection of said third portion with said second portion to the free edge of said first portion, the amount of such reduc- 75

tion in wall thickness being proportioned to cause a variation in the area of contact of the first portion with the cylinder wall in direct proportion to the fluid pressure imposed upon the ring between the first and second portions thereof.

8. In combination, a piston, a circular plate mounted on the end of said piston and having a raised portion upon its outwardly facing surface of smaller diameter than said plate, a hollow piston ring seated upon said plate and surrounding said raised portion thereof to be centered thereby in respect to said piston, said ring being made of resilient metal and having a first portion surrounding said plate and directed toward the end of said piston, a second portion hollow cylindrical

in form surrounding and spaced from the first portion and extending toward the piston end, and a third portion integrally connecting said first and second portions adjacent the piston end but being spaced therefrom, said second and third portions being tapered by a reduction in wall thickness from the first portion to the free end of said second portion, the reduction in thickness of the walls of said second and third portions being proportioned to insure that the area of contact of said second portion with the cylinder wall will vary in direct proportion with the fluid pressure imposed thereon between said first and second portions.
